UNITED STATES PATENT OFFICE.

MELVIN HOLLOWELL, OF NORWALK, IOWA.

ATTACHMENT FOR HAY-TRACKS.

1,174,420.

Specification of Letters Patent.

Patented Mar. 7, 1916.

Application filed July 21, 1915. Serial No. 41,187.

To all whom it may concern:

Be it known that I, MELVIN HOLLOWELL, a citizen of the United States, and resident of Norwalk, in the county of Warren and State 5 of Iowa, have invented a certain new and useful Attachment for Hay-Tracks, of which the following is a specification.

It is commonly known that in the installation of hay tracks in barns and the like, it 10 is desirable to have one end of the track project beyond the end of the barn, and where the tracks do so project the builder faces the problem of suitable means for supporting and bracing such projecting end.

15 The object of my invention is to provide an attachment for tracks of this kind of simple, durable and inexpensive construction, whereby the projecting end of the track may be properly supported, and also may be held 20 rigidly in line and against twisting or bending.

25 A further object is to provide such an attachment including a pair of plates properly constructed for frictionally gripping between them the track at any point in its length, connected with proper supporting rods for holding the track against the greatest strain imposed thereon, which is the 30 downward strain and also for holding the track against lateral twisting movement.

35 My invention consists in the construction, arrangement and combination of the various parts of the device, whereby the objects contemplated are attained, as hereinafter more 40 fully set forth, pointed out in my claims, and illustrated in the accompanying drawings, in which:

45 Figure 1 shows a front elevation of a barn or similar structure in which is a hay track equipped with an attachment embodying my invention. Fig. 2 shows a front elevation of the track and the attachment installed thereon. Fig. 3 shows a side elevation of the same, and Fig. 4 shows a top or plan view of the attachment.

50 In the accompanying drawings I have used the reference numeral 10 to indicate the upper portion of the front end of the barn. Suitably mounted in the barn is a track extending forwardly from the barn and comprising the upwardly and downwardly extending members 11 and 12 and the central opposite laterally extending members 13. The upper portion 11 has at 55 its upper part a ball 14 forming the track on which the cage runs.

It is understood that the track projects forwardly from the barn to permit hay to be raised and then drawn into the barn. In order to properly support the projecting end 60 of the track, I have provided my improved attachment, which comprises a plate 15 having a central, longitudinal, upwardly extending rib 17 in which is an opening 18. The lower surface of the plate 15 is provided 65 with a central longitudinal groove 19 to receive the upper portion 11 of the track.

70 The plate 15 is provided on each side of the portion 17 with a pair of spaced openings 20 to receive bolts. The openings 20 are so located that the bolts extended through them will just clear the portions 13 of the track. The plate 15 is also provided with larger openings 21 spaced from each other on the transverse median line of the 75 plate to receive the rods hereinafter referred to. A coacting plate 22 is provided having a flat upper surface provided with a longitudinal groove 23 in its central portion adapted to receive the portion 12 of the 80 track. The plate 22 is narrower from side to side than the plate 15, and is provided with openings similar to the openings 20 to register therewith. The plates are adjacent to each other, as shown in Fig. 2, with 85 the track received between them, as shown, and are bolted together by means of bolts 24 and nuts 25. It will be seen that the means for connecting the two plates are adjustable, so that the plates may be used with 90 tracks of different sizes so that the frictional engagement between the track and the plates may be made as firm as desired.

95 The plates are installed on the track at the proper distance from the barn, and in this connection attention is called to the advantage of having the plates connected with the track by frictional engagement, whereby they may be secured at any point in the length of the track, so that my improved attachment may be used on tracks located at different heights from the top of the barn and extending different distances from the front of the barn.

100 For securing the attachment in position for thereby rigidly supporting the track and preventing its twisting and lateral movement, I have provided a rod 26 having at its lower end a hook 27 at the end of which is a slightly upturned part 28. The 105 hook 27 is adapted to enter the opening 18. The upper end of the hook 27 is pivotally 110

secured to a yoke 29 fastened to the end of the ridge pole or central part of the roof of the barn or the like. Other rods 30 are adapted to be inclined outwardly and laterally from the plates 15 and 22 and are provided at their lower ends with hooks 31. The holes 30 in the plate 15 and the hooks 31 are so arranged that the hooks can be inserted from the door way where the builder 5 cannot reach the plates. The rods 30 are then swung up to proper position, without necessity for scaffolding or the like, and secured to the upper ends of the rafters in any suitable way.

15 It will be seen by varying the position of the points 33 where the rods 30 are secured to the rafters the attachment may be adjusted to suit the position of the track and the pitch of the barn roof. It will also 20 be noted that the rods 30 are not only inclined laterally from the plates 15 and 22, but also toward the front of the barn, and that on account of the fact that the member 31 is vertical, the members 30 can be 25 swung to proper position without difficulty.

It will readily be seen that my device may be used for supporting the outer end of a litter carrier track or the like, by adjusting the length and points of attachment of the 30 members 26 and 30. Sufficient play of the parts is allowed to permit slight turning of the track, but not sufficient to permit swinging the track out of line, or seriously twisting it. It may be mentioned that tracks 35 of this type are hung to swing slightly to allow a straight feed on the carrier and the parts of my device are arranged to permit such swing. This is accomplished by allowing the upper plate to slide or turn slightly 40 on the hook members. This allows sufficient flexibility of the device to protect the track.

Some changes may be made in the construction and arrangement of the parts of

my improved device without departing from its essential features and purposes, and it is 45 my intent to cover by this application any such changes which may be included within the scope of my claims.

I claim as my invention:

1. In a device of the class described, a 50 clamp for a track including a member having an upwardly extending lug, openings in said member, rods having hook members to enter said openings, said rods and openings being arranged to permit the member to 55 move on the rods to permit tilting of the track.

2. In a device of the class described, a plate, having on its upper surface a central upwardly extending lug provided with an 60 opening and having in its lower surface a groove to receive part of a track, a second plate having in its upper surface a groove to receive part of a track, means for adjustably securing said plates together for 65 gripping a track between them, said plates having on opposite sides of said grooves, openings to receive supporting rods, rods extended through said openings having parts for engaging the under surfaces of the 70 upper plate.

3. In a device of the class described, an upper plate having in its lower surface a groove to receive part of a track, a lower plate the upper surface of which is designed 75 to engage track, means for adjustably securing said plates together for gripping a track between them, means for securing the central portion of the upper plate to a support and detachable means for securing the sides 80 of both plates to a support.

Des Moines, Iowa, July 3, 1915.

MELVIN HOLLOWELL.
